UNITED STATES PATENT OFFICE.

HERMAN G. TORKE, OF PLYMOUTH, WISCONSIN.

ROAD SCRAPER OR DRAG.

1,322,974.

Specification of Letters Patent. Patented Nov. 25, 1919.

Application filed April 20, 1917, Serial No. 163,839. Renewed May 8, 1919. Serial No. 295,709.

To all whom it may concern:

Be it known that I, HERMAN G. TORKE, a citizen of the United States, and resident of Plymouth, in the county of Sheboygan and State of Wisconsin, have invented certain new and useful Improvements in Road Scrapers or Drags; and I do hereby declare that the following is a full, clear, and exact description thereof.

10 My invention relates to certain new and useful improvements in road scrapers or drags and refers particularly to improvements in what is generally known to the trade as King drags, employing a scraping member comprising two forward inclined blades and a central rear blade for leveling the earth.

15 The primary object of the present invention is to provide novel and efficient means for lifting the scraping member from engagement with the surface of the road.

20 A further object of my invention is the provision of means for selectively tilting either side of the scraping member to give the crown of the road its proper angle.

25 And a still further object of this invention is to provide means for securing the scraping member in the desired adjusted position; and to further provide means for 30 equally distributing the draft of the scraper.

With the above and other objects in view which will appear as the description proceeds, my invention consists in the novel construction, combination and arrangement of 35 parts, substantially as hereinafter described and more particularly pointed out in the appended claims, it being understood that changes in the precise embodiment of the invention herein disclosed can be made without departing from the spirit of the invention.

40 In the accompanying drawings I have illustrated one complete example of the physical embodiment of my invention constructed according to the best mode I have so far devised for the practical application of the principles of my invention.

45 Figure 1 is a view in plan looking at the underneath of my invention.

50 Fig. 2 is a view in elevation looking at the rear end thereof.

55 Fig. 3 is a view in side elevation of my road scraper, the road scraping member being shown as lifted from engagement with the road surface.

Fig. 4 is a view similar to Fig. 3, the road scraping member being shown as in operative position.

Fig. 5 is a detail view of the means for locking the truck in its adjusted position, 60 and

Fig. 6 is a detail view of the pawl and ratchet used to retain the scraper member in its adjusted position.

65 My invention is used in connection with what is termed as a King drag or scraper, comprising the ballast receiver 1, carrying the two oppositely inclined scraper blades 2, and the central evening blade 3, all of well known construction, and this scraping member 70 is operated or drawn by means of the extensible truck 4, having the usual fore guiding wheels 5, carrying the tongue 6 for attachment thereto of any suitable draft means which may be horses or any mechanical tractor, and the rear wheels 7 mounted upon the extension 8 slidably mounted upon the side members 9 of the truck 4, as hereinafter described.

75 This extension 8 consists of the two side 80 members 10 extending parallel with the sides of the truck and have secured to their ends the sliding collars or sleeves 11 engaging the side members 9 of the truck, and supported from the rear pair of said sleeves 11 is the 85 axle 12 for the wheels 7, suitable braces or trusses 13 being provided for the extension, running from the rear axle to the forward end of the side members 10.

80 For operating the extension 8 to lengthen or shorten the wheel base of the truck, a rack 14 is secured to each of the sides 9 of the truck near the rear end thereof, having in mesh therewith the gear pinions 15 carried by a shaft 16 journaled in bearings 90 mounted upon the extension side members 10. Fixed to this shaft 16 is the manually operated wheel 17 for operating the pinions to lengthen or shorten the truck, as will be readily apparent, and for locking or retaining the truck in its adjusted position, a brake band 18 is employed engaging a drum 19 carried by the wheel 17 and operated by the hand lever 20 having the usual pawl and ratchet 21 for securing the same in adjusted 95 position.

100 By reference to Figs. 3 and 4 of the drawings it will be readily seen that when the truck is extended the scraping member is 110 lifted from engagement with the surface of

the road and that when the truck is shortened the scraping member is allowed to engage the road's surface. This is accomplished by means of the draw connections 22 secured at one end to the inclined blades and at their forward ends to the truck, the outer connections being secured at 23 to the side members 9, and the inner connections being secured at 24 to the front 10 bolster, and the chain or other connections 25 connected, one at each side of the blade 3 and at 26, to the extension 8.

Thus it will be seen that when the truck is extended the draw connections 22, which 15 may be chains, or any desired connections, and the chains 25 are tightened, thus lifting the scraping member, as will be obvious; and to support this great strain the truck is braced by the trusses 27.

20 In order to tilt the scraping member to give the proper crowning to the road, the hand wheels 28 fixed to the shafts 29 carrying on their outer ends the drums 30, are employed. These shafts 29 are journaled 25 in bearings 31 secured to the trusses 27, and are supported or independently secured in place between the trusses by means of the sleeve 32. Fixed to the scraping member at 33 are the ropes or other connections 34 having their free ends engaging the drums 30, and to secure the scraping member in its adjusted position, the ratchets 35 are employed secured to each shaft 29 intermediate the wheels 28 and the trusses, 35 and adapted to be engaged by the pawls 36 carried by said trusses, as shown in Fig. 6.

From the foregoing description taken in connection with the drawings the operation 40 of my invention will be readily apparent and further description is thought unnecessary, and so to equalize the draft to insure the proper scraping of the road a suitable draft equalizer 37 is employed, having the 45 connections 38 leading to the scraping member.

What is claimed is:

1. A road scraper comprising a supporting frame including extensible sections, a 50 road scraping member having connections with the sections, and means for extending the frame to lift the scraping member from operative position.

2. A road scraper comprising a portable 55 extensible truck, a road scraping member intermediate the ends thereof, flexible connections between the scraping member and the truck, said connections leading from the rear and front portions of the scraping 60 member to the rear and front portions respectively of the truck, and means for extending said truck to lift the scraping member from operative engagement with the surface of the road.

65 3. A road scraper comprising a portable

extensible truck, a road scraping member, draw connections leading from the forward end of the scraping member to the forward end of the truck, flexible connections leading from the rear end of said scraping member to the rear extension of the truck, and rack and pinion means for extending said truck to tighten the connections between the scraping member and the truck to lift the same from operative position. 75

4. A road scraper comprising, a portable truck member, an extensible member slidably secured to the truck, a scraping member, flexible connections leading from the scraping member to said truck and extension, means for lengthening the truck to lift the scraping member from operative position, and means for retaining the scraping member in lifted position. 80

5. A road scraper comprising a portable truck member, an extensible member slidably secured to the truck, a scraping member, connections leading from the scraping member to said truck and extension, means for lengthening the truck to lift the scraping member from operative position, and brake means for retaining the scraping member in lifted position. 90

6. A road scraper comprising a portable extensible truck, a scraping member carried by the truck and adapted to be lifted or lowered by the adjusting of the truck length, means for retaining the truck in its adjusted position, and means for tilting the scraping member to give the desired crowning to the road being repaired. 95

7. A road scraper comprising a portable truck member, an extensible member slidably secured to the truck, a scraping member having flexible connections with said truck and extension, a rack bar carried by the truck and means operating thereon for lengthening the truck to lift the scraping member from operative position. 105

8. A road scraper comprising a portable truck member, an extensible member slidably secured to the truck, a scraping member having flexible connections with said truck and extension, a rack bar carried by the truck, a pinion gear engaging said rack for lengthening the truck to lift the scraping member from operative position, a drum mounted upon the shaft of said pinion, and means engaging said drum for retaining the scraping member in lifted position. 110

9. A road scraper comprising a portable truck member including longitudinal sills, an extensible member mounted thereon and having slots slidably engaging said sills, a scraping member, flexible connections leading from the scraping member to the truck and extension, and means carried by said extension engaging the rack bars carried by the sills for extending the truck length to lift the scraper from operative position. 125

10. A road scraper comprising a portable truck member including longitudinal sills and braces therefor, an extensible member slidably secured to the truck, a scraping member, flexible connections leading from the scraping member to said truck and extension, rack bars fixed to the sills, a transverse shaft journaled in the extension, pinion gears carried by said shaft and meshing with said rack bars, and hand operated means mounted upon the shaft for extending the truck length to lift the scraper from operative position.

5

11. A road scraper comprising a portable truck member, said truck being extensible, a scraping member carried by the truck and

15

adapted to be lifted and lowered by the adjusting of the truck length, and means for tilting the scraping member to give the desired crowning to the road being repaired, 20 said means comprising a collar transversely of the frame, split shafts journaled in said collar, drums carried by the ends of the shafts, connections between said drums and the ends of the scraping members and means 25 for revolving the shafts.

In testimony that I claim the foregoing I have hereunto set my hand at Milwaukee, in the county of Milwaukee and State of Wisconsin.

HERMAN G. TORKE.
